US0D1094708S

(12) **United States Design Patent** (10) **Patent No.:** **US D1,094,708 S**
(45) **Date of Patent:** **** Sep. 23, 2025**

(54) **NEGATIVE PRESSURE WOUND THERAPY TUBING CONNECTOR**

(71) Applicant: **DeRoyal Industries, Inc.**, Powell, TN (US)

(72) Inventors: **Dhanvin S. Desai**, Knoxville, TN (US); **Scott D. Barnes**, Knoxville, TN (US); **Walter C. Cowart**, Blaine, TN (US); **Jonathan M. Cayce**, Knoxville, TN (US); **Andrew Sullivan**, Knoxville, TN (US); **Vincent D. Jardret**, Powell, TN (US); **Breanna J. Rhyne**, Powell, TN (US)

(73) Assignee: **DeRoyal Industries, Inc.**, Powell, TN (US)

(**) Term: **15 Years**

(21) Appl. No.: **29/922,299**

(22) Filed: **Dec. 21, 2023**

CLAIM

The ornamental design for a negative pressure wound therapy tubing connector as shown and described.

DESCRIPTION

FIG. 1 is an overhead perspective view of a negative pressure wound therapy tubing connector of our new design; FIG. 2 is a front elevational view of the negative pressure wound therapy tubing connector of FIG. 1; FIG. 3 is a rear elevational view of the negative pressure wound therapy tubing connector of FIG. 1; FIG. 4 is a top plan view of the negative pressure wound therapy tubing connector of FIG. 1; FIG. 5 is a bottom plan view of the negative pressure wound therapy tubing connector of FIG. 1; FIG. 6 is a left-side elevational view of the negative pressure wound therapy tubing connector of FIG. 1; and, FIG. 7 is a right-side elevational view of the negative pressure wound therapy tubing connector of FIG. 1.
